LOOSE-LEAF BINDER

John Schade, Holyoke, Mass., assignor to National
Blank Book Company, Holyoke, Mass., a corpo-
ration of Massachusetts

Original application April 24, 1939; Serial No.
269,556. Divided and this application July 17,
1940, Serial No. 346,011

7 Claims. (Cl. 129—17)

This invention relates to an improved loose leaf binder particularly of the type used to hold loose leaf sheets of the visible index bookkeeping kind. In such binders, the user, in addition to inserting new sheets, frequently wants to shift some of the visible index sheets longitudinally of the back to change, for instance, their chronological or alphabetical order. According to the present invention, the binder is constructed to provide for the utmost flexibility and simplicity of action for this purpose and at the same time has numerous novel features which render the structure more satisfactory and serviceable over a period of rough use such as these binders are subjected to.

This application is a divisional case of my copending application Serial No. 269,556, filed April 24, 1939.

The manner in which my structure has been arranged to accomplish the desired results can best be understood from a reading of the specification in connection with the accompanying drawings, in which:

Fig. 1 is a top plan view of the binder, with the covers opened and broken away to save drawing space, and showing the prong sets in one of several overlapped positions determined by a latching mechanism;

Fig. 2 is a sectional view on line 2—2 of Fig. 1;

Fig. 3 is a top plan view of a sufficient part of the right hand portion of Fig. 1 to show how the prong sets may be offset longitudinally an amount equal to the distance between a pair of binding holes in an index sheet;

Fig. 4 is a view of the parts of Fig. 3, but illustrating how these parts may be manipulated so that the prong sets are offset longitudinally twice the space between binding holes;

Fig. 5 is an enlarged sectional view on line 5—5 of Fig. 4; and

Fig. 6 is a side elevation taken on line 6—6 of Fig. 2.

In general, the binder structure herein disclosed has latching mechanism for holding the binder with the prongs in various degrees of overlap and a novel slide mechanism for changing the longitudinal position of the prongs. Inasmuch as the latching mechanism is dealt with at length and is the subject matter of the claims in my copending application referred to, I will only describe it in sufficient detail so its operation may be understood and will deal principally with the novel slide mechanism.

Referring first to Figs. 1, 2, and 6, the binder consists generally of a pair of Z-shaped angular

back plates 5 and 6 having their short depending legs 3 pivoted together by means of a piano hinge at 7. The long upstanding legs 8 and 9 terminate in a series of spaced hinge eyes 11 to which are pivoted covers 12 and 13 by means of hinging strips 14 and 15 which have hinge eyes 16 that are complementary to hinge eyes 11 and pivotally connected thereto as indicated. Secured to each of the long legs 8 and 9 of plates 5 and 6 by any suitable means is an anchor plate 17 and a hood member 18, this last to prevent the binder from scarring surfaces on which it may be used and to add a finished appearance. Each anchor plate 17 has a series of hook-shaped tongues 20 which extend laterally from the top edge of the plates through the spaces between hinge eyes 11 to form a track for the prong carrying plates 21 and 22 having a series of prongs 23 and 24, respectively, which extend in an arc over the plates 5 and 6 (see Fig. 2). Plates 5 and 6 are notched midway between their ends as at 25 and 26 to provide for a pair of latch members 27 and 28 having gooseneck extensions of the same curvature. As is indicated, member 27 is fixedly attached to the bottom of plate 5 and has its gooseneck portion extending through notches 25 and 26 and underlying plate 6 (see Fig. 1). The latch member 28 is, on the other hand, pivotally connected as at 28' to the bottom of plate 6 and has its gooseneck portion extending through notches 25 and 26 and underlying plate 5. Along one edge, member 28 has a nose or dog 29 which can engage a series of shoulders 30, 31, 32, formed as serrations along the adjacent edge of member 27 to allow the plates 5 and 6 to be held in various angular positions around the pivot 7 to thereby change the overlap of the prongs 23 and 24. On the opposite edge, member 28 has a pair of cam surfaces 33 and 34. As is more fully described in my copending application, when the dog 29 is released from engagement with the notch 30 by rotating member 28 about its pivot 28' and the plates 5 and 6 are rotated around hinge 7 from the position of Fig. 1, cam surfaces 33 and 34 cooperate with the top edge 35 of slot 25 to act as an escapement and force dog 29 successively into engagement with shoulders 31 and 32. To rotate member 28 to release the latch mechanism, a trigger rod 36 is provided which is in the form of a long flat bar with oppositely disposed offset ends 37 and 38 and which is positioned to lie parallel to and inside of the depending leg 3 of plate 6 (see Figs. 1 and 5). Trigger rod 36 is dimensioned so that the offset 38 lies beyond the lower end of the binder to provide a

convenient handle. Offset 37 protrudes through a slot cut in the depending leg 3 of plate 6 (see Fig. 6) and forms a support for that end of the trigger rod. Where the trigger rod underlies latch member 28 it has an upstanding integral lug 39 which passes through a hole in member 28. A spring 40 (see Figs. 5 and 6) is tensioned about depending lugs 41 and 42 on plate 6 and has its end engaging a shoulder 43 on trigger rod 36, the spring being wound to force the trigger rod 36 in a direction to engage members 27 and 28. Thus the user may disengage latch member 28 from member 27 by simply pressing on offset 38, the upper end of notch 26 in plate 6 being provided with a slot 44 located on the depending leg 3 to allow for the motion of member 28.

From the above it will be clear that the user may change the overlapped relation of the prong sets 23 and 24 by simply pressing the offset end 38 of member 36 successively and allowing the plates 5 and 6 to fall to spread positions around hinge 7 by their own weight. These spread positions are of course those determined by the engagement of nose 29 of member 28 with serrations 30, 31, and 32 on the fixed latch member 27.

It is believed that the foregoing will make sufficiently clear for the purposes of this disclosure the operation of the latching mechanism, and I will therefore now describe in detail the novel slide mechanism with which this case is chiefly concerned.

Referring again to Figs. 1, 2 and 6, plate 21 is a simple flat plate which lies parallel to the long leg 8 of plate 5 while plate 22 is angular in cross section with the short leg 45 of the angle overlying the flat surface of plate 6. In the binder herein shown plate 21 is stationary, being secured to leg 8 in any suitable manner as for instance by spot welding, while plate 22 may slide longitudinally in the trackway formed by the tongues 20 of the right hand anchor plate 17 to thereby vary the relative longitudinal position of prongs 23 and 24. As appears in Figs. 1 and 2, overlying short leg 45 of plate 22 is a short angular rack member 46 having its toothed portion extending downwardly through a slot 47 in plate 6. Rack member 46 has its teeth in engagement with pinion teeth 48 on a pinion 49 pivoted at 50 to the bottom of plate 6. As is clear from Fig. 1, prong carrying plate 22 may be moved longitudinally to displace the prong set 24 by merely rotating pinion 49 about its pivot 50, the depending arm of the rack 46 by cooperation with slot 47 serving to guide one end of the lower edge of plate 22. The other end of the lower edge is guided by clip 51 preferably riveted as shown to plate 6 and overlying the short angular leg 45 of plate 22.

In addition to pinion teeth 48, pinion 49 has a set of pinion teeth 52 (see Fig. 1) which are formed on a larger radius than teeth 48. The extremities of these teeth 52 extend through a slot cut in a depending leg 3 of plate 6 and are engaged by a series of slots 53 cut in a depending skirt of an angular slide 54 which overlaps plate 6 (see Figs. 1, 2 and 6) and may slide between limits thereon parallel to the axis of the central hinge 7.

At its forward end the slide 54 has a pair of downwardly directed tabs 55 struck out of the material of the slide, the tabs extending through a slot 56 cut in plate 6 with their extremities rebent to underlie the bottom surface of plate 6 and secure the forward end of slide 54 to said plate (see Fig. 3). Towards its lower end slide 54 has secured to it a pin 57 extending through a slot 58 likewise cut in plate 6. As is shown in Fig. 5,

this pin 57 has an enlarged head underlying plate 6 to maintain this end of the slide 54 in sliding contact with plate 6.

Comparing Figs. 1 and 4, it will be seen that the slots 56 and 58 in plate 6 are dimensioned so that they act to limit the motion of slide 54 to the two extreme positions to which pinion 49 can be moved by cooperation of gear teeth 52 and slots 53 (see also Fig. 6). As will also be apparent from these figures, when the slide 54 passes from its normal position of Fig. 1 to its maximum displaced position of Fig. 4, the prongs 24 have been displaced longitudinally from prongs 23 a distance corresponding to twice the distance between adjacent binding holes in the binding sheets. To make this clear note in Fig. 4 the distance between lines X and Z which shows the displacement of prong 24 from the position of Fig. 1 while the distance X-Y is the normal distance between binding holes in the index sheet.

While the mechanism just described provides for a longitudinal prong offset equal to twice the distance between binding holes in index sheets, I have found that normally an offset just equal to the distance between binding holes is the most likely to be used. I have therefore provided a specially constructed handle which not only serves as a convenient means to shift slide 54 but also is constructed so that it may be rocked to two different positions, in the first of which it limits the motion of slide 54 to half its normal or full stroke so that the longitudinal displacement of prongs 24 is only equal to the distance between binding holes, and in the second of which it allows for the full stroke of slide 54. Referring to Figs. 3-5 and 6, this handle consists of a flat angular member 59 having a vertical offset 60 at one end and pivoted as at 61 near the lower end of slide 54. A short leaf spring 62 is riveted to member 59 and presses into either of two seats 65 and 66 provided in member 54, a small ball bearing 63 which can pass freely through a hole 64 in member 59 (see Fig. 5). At the lower end slide 54 likewise has a vertical stop 67 and a rebent keeper 68 formed integrally from the material of the slide as shown. This stop 67 and the keeper 68 limit the rotation of member 59 about pivot 61 to the two positions shown by Figs. 3 and 4 while the ball 63 acts as a spring pressed detent to maintain the member 59 in either position.

Member 59 has a nose 69 formed at its forward end and in the position of member 59 shown in Fig. 3, this nose overlies a slot 70 in slide 54. Extending upwardly through slot 70 is a tongue 71 struck up from plate 6. Therefore if the handle 59 is left in the position of Fig. 1 and the slide 54 moved by grasping vertical offset 60, the nose 69 contacts the tongue 71 and the motion of the slide is limited to one-half the maximum distance possible, the prongs being displaced only the distance X-Y, that is the distance between successive binding holes (see Fig. 3).

From the above it is clear that the user is allowed a choice of the amount of longitudinal displacement to be given the prongs and can control the displacement by merely shifting the handle 59. This feature makes the binder extremely well suited for rapid use in shifting operations of more than one kind or distance, and when combined with the latch mechanism already described and which controls the overlapped relation of the prong sets results in various desirable binder manipulations being possible and more conveniently than heretofore.

The extreme flexibility of this binder will be

readily apparent because as will be remembered, the offset relation of the prongs can be varied at any time independently of the over-lapped relation and the amount of variation which is produced can itself be varied. The operation in varying the longitudinal relation of the prong sets resolves itself simply to sliding the slide 54 to either of its two positions as determined by the position of member 59, while the overlapped relation is varied by a separate manipulation of the trigger 36.

It will be seen from the foregoing that I have produced a binder for the purpose described which though considerably involved in mechanical detail has been so arranged that its operation from the standpoint of the user is much simpler and allows for more rapid work.

I claim:

1. A binder having a back portion including two hingedly connected plates, a set of prongs supported at the side edge of each plate, a slidable bar carrying one set for movement longitudinally of one plate, an operating slide associated with said plate and reciprocable relative to said plate to and from a normal and an extended position, members connecting said slidable bar and operating slide for transferring reciprocation from the slide to the bar, a handle for reciprocating the operating slide and means to selectively limit the reciprocation of said slide to and from the normal position and a point intermediate of said normal and extended positions.

2. A binder having a back portion including two hingedly connected plates, a set of prongs supported at the side edge of each plate, a slidable bar carrying one set for movement longitudinally of one plate, an operating slide associated with said plate and reciprocable longitudinally relative to said plate to and from a normal and an extended position, members connecting said slidable bar and operating slide for transferring reciprocation from the slide to the bar, a handle for reciprocating the operating slide, means selectively engageable by the handle for limiting the movement of said slide to and from the normal position and a point intermediate said normal and extended positions.

3. A binder having a back portion including two hingedly connected plates, a set of prongs supported at the side edge of each plate, a slidable bar carrying one set for movement longitudinally of one plate, an operating slide associated with said plate and reciprocable longitudinally relative to said plate to and from a normal and an extended position, members connecting said slidable bar and operating slide for transferring reciprocation from the slide to the bar, an operating handle for said slide pivoted to said slide and rockable to two positions, means engageable by the handle in one of its two rocked positions for limiting the reciprocation of the slide to and

from the normal position and a position intermediate the normal and extended positions.

4. A binder having a back portion including two hingedly connected plates, a set of prongs supported at the side edge of each plate, a slidable bar carrying one set for movement longitudinally of one plate, a pinion pivoted on one back plate and having two sets of gear teeth, the respective sets having different pitch diameters, a rack bar attached to said slidable bar and in engagement with the set of pinion gear teeth of smaller diameter, a reciprocable pinion plate associated with one back plate and having teeth in engagement with the set of pinion gear teeth of larger diameter and being reciprocable to and from a normal and an extended position for longitudinal movement of said slidable bar, a handle on the pinion plate movable to two positions, means engageable by the handle in one of the two positions for limiting the reciprocation of the slide to and from the normal position and a position intermediate the normal and extended positions.

5. A binder having a back portion including two hingedly connected plates, a set of prongs supported at the side edge of each plate, a slidable bar carrying one set for movement longitudinally of one plate, a rack bar attached to said slidable bar, a pinion on one back plate engaging said rack bar, a slidable pinion plate associated with one back plate for operating said pinion between two determined limits, and means on said pinion plate and one back plate cooperable to releasably limit the motion of said pinion plate to a point intermediate the aforesaid limits, all for the purpose described.

6. The structure of claim 5 with said means on said pinion plate consisting of a handle on the pinion plate movable to two positions and adapted in one position to engage a lug on the back plate which is associated with said pinion plate to limit the motion of said pinion plate to said intermediate point, and in the other position to allow motion of the pinion plate between its extreme limits.

7. A binder having a back portion including two hingedly connected plates, a set of prongs supported at the side edge of each plate, a slidable bar carrying one set for movement longitudinally of one plate, a rack bar attached to said slidable bar, a pinion on one back plate engaging said rack bar, a slidable pinion plate associated with one back plate for operating said pinion between two determined limits, a handle on the pinion plate movable to two positions and adapted in one position to engage a lug on the back plate which is associated with said pinion plate to limit the motion of said pinion plate to said intermediate point, and in the other position to allow motion of the pinion plate between its extreme limits, and detent means to releasably secure said handle in either of its two positions.

JOHN SCHADE.
